UNITED STATES PATENT OFFICE.

GEORGE VINCENT, OF DARLINGHURST, SYDNEY, NEW SOUTH WALES, AUSTRALIA.

EVAPORATOR.

Application filed September 26, 1922. Serial No. 590,660.

To all whom it may concern:

Be it known that I, GEORGE VINCENT, a subject of the King of Great Britain, residing at Darlinghurst, Sydney, in the State of New South Wales, Commonwealth of Australia, have invented certain new and useful Improvements in Evaporators, of which the following is a specification.

This invention has reference to evaporators employed in different industries for taking up or extracting moisture from articles such as fruit, vegetables, grain, fish, meat, copra, chemicals, leather, and such like. The main object of my invention is to utilize the flue gases to a greater extent than has been possible in existing apparatus.

According to my invention, the main flue pipe is extended approximately horizontally from the furnace or stove, under the drying chamber, to adjacent the opposite end of said chamber. At this point the main flue pipe is connected to two smaller parallel flue pipes by means of a suitable junction coupling, such as a T pipe, returning the flue gases past the chamber in which the furnace is fixed, said pipes being connected by a bifurcated junction to a vertical flue pipe leading to the atmosphere. In order to overcome the resistance of the horizontal flues, increase the velocity of the flue gases, and ensure proper combustion of the fuel, I preferably provide an induced draft pipe, air nozzle, or the like adjacent the said bifurcated junction, which is supplied with air under pressure in the heating chamber and discharges such air through the smoke stack.

The air for evaporating purposes is drawn from the atmosphere by means of a centrifugal fan positioned at the ends of the flue pipes situated at the air outlet end of the evaporating chamber and is forced parallel with said pipes forming a plenum or pressure in the enclosure surrounding said pipes and in a heating chamber situated above the furnace. From said heating chamber the heated air passes into the evaporating chamber through a panel or partition having adjustable openings whereby the volume and temperature of the air currents are controlled. The pressure of air in the heating chamber provides the necessary velocity pressure in the induced draft pipe.

Referring to the accompanying sheet of drawings,

Figure 1 is a plan view of the apparatus with treating chamber removed, while

Figure 2 is a sectional elevation of the complete apparatus.

Figure 3 is a sectional plan view on line 3—3, Figure 2. 60

Figure 4 is a sectional view on line 4—4, Figure 2, on an enlarged scale of the flues and drying chamber, while

Figure 5 is a similar view on line 5—5, Figure 2, of the furnace and smoke flues. 65

Figure 6 is a sectional elevation of a modified form of apparatus, and

Figure 7, a sectional plan view on the line 7—7, Figure 6. 70

Figure 8 is a cross sectional elevation on the line 8—8, Figure 7. 75

The same numerals indicate like parts throughout the drawings.

25 is the fan or blower the air from which is forced around the main flue 12, branch 75 passages 13 and 14 coupling with return flues 9 and 9^A positioned in the flue or plenum enclosure or chamber 23. The furnace 10 is in communication with the main flue 12 and its smoke stack 11 is coupled to the branch 80 passages 13, 14. The ends of the tubes 9 and 9^A are provided with doors or the like 15 for cleaning purposes and at their junction with the flue 11, I have an induced draft pipe 11^A which operates as before stated. 85

16 is the drying and treating chamber superimposed upon the air heating tubes 12, 9 and 9^A. The said chamber is provided with a series of rollers 17 on its floor by which the fruit or other articles being treated are supported on suitable trays or the like (not shown) and fed through the door 18 into the chamber 16, and after passing along same are removed through a door 19 in the side. 95

The heated air is delivered from the chamber 24 above the furnace into the treating chamber 16 through the panel 20 adjacent the furnace end. This panel is composed of slats each of which is adjustable so as to permit ready alteration of the volume of heated air forced into the treating chamber. The fan or blower 25 is revolved by an engine 21 and suitable pulleys and belting 22. 100

In the modification shown in Figures 6, 7 and 8, 26 is the flue chamber with furnace 27. 28 is a flue pipe leading therefrom, and 29 and 30 are further flue pipes connected to the pipe 28 by branches 31 and 32. 33 and 34 are the blower fans with outlets 35 and 36 respectively. 37 is the smoke stack connected to the flues 29 and 30 by upwardly ex- 110

tending pipes 38 and 39, and 40 is a pipe to cause induced draft to the stack. 41 is the treating chamber open at both ends and through which the materials being treated are passed on trays or trucks on the rollers 42. The heated air, after passing through the chamber 26, is forced into the treating chamber 41 through the perforated plates 43 and 44. Materials to be treated can be 10 passed through from either end, said ends being closable by the doors 45. Further perforated plates 46 are placed at the opposite end to the furnace through which some of the heated air passes through the treating 15 chamber 41 is again drawn into the fans.

I claim:

1. In an evaporator, a structure forming an evaporating chamber, and a chamber therebelow, a furnace arranged to heat said 20 evaporating chamber, a smoke stack for the furnace, a flue from the furnace arranged in the chamber below the evaporating chamber and discharging into the smoke stack, and means to force air to the evaporating chamber through the chamber therebelow and around the exterior of said flue.

2. In an evaporator, a structure forming an evaporating chamber, and a chamber therebelow, a furnace arranged to heat said 30 evaporating chamber, a smoke stack for the furnace, a flue from the furnace arranged in the chamber below the evaporating chamber and discharging into the smoke stack, and a blower to force air to the evaporating 35 chamber through the chamber therebelow and around the exterior of said flue.

3. In an evaporator, a structure forming an evaporating chamber, a chamber therebelow, a chamber at one end of the evaporating 40 chamber, a furnace below the last named chamber, a flue leading from the furnace into and returning from the lower chamber, a smoke stack into which said flue dis-

charges and the intake portion of which is arranged in the chamber at the end of the 45 evaporating chamber, and a blower to force air through the lower chamber, around the exterior of said flue and through said end chamber and from thence through the evaporating chamber. 50

4. In an evaporator, a structure forming an evaporating chamber, a chamber therebelow, a chamber at one end of the evaporating chamber, a furnace below the last named chamber, a flue leading from the 55 furnace into and returning from the lower chamber, a smoke stack into which said flue discharges and the intake portion of which is arranged in the chamber at the end of the evaporating chamber, a blower to force air 60 through the lower chamber, around the exterior of said flue and through said end chamber and from thence through the evaporating chamber, and an induced air draft pipe discharging from said end chamber into said smoke stack.

5. In an evaporator, a structure forming an evaporating chamber, a chamber therebelow, a chamber at one end of the evaporating chamber, a furnace below the last 70 named chamber, a flue leading from the furnace into and returning from the lower chamber, a smoke stack into which said flue discharges and the intake portion of which is arranged in the chamber at the end 75 of the evaporating chamber, a blower to force air through the lower chamber, around the exterior of said flue and through said end chamber and from thence through the evaporating chamber, and a partition between the evaporating chamber and said end chamber and having openings for the passage of air therethrough. 80

In testimony whereof I have hereunto set my hand.

GEO. VINCENT.
